BRIDGE

George Van Eps, North Hollywood, Calif.

Application June 29, 1946, Serial No. 680,382

5 Claims. (Cl. 84—309)

1

The present invention relates to a bridge construction of the type which is used for stringed instruments. Specifically, the invention relates to a bridge for use with bass violins.

It has heretofore been customary for the violinist to be provided with two bass violins, one for use while practicing and one for use when performing before an audience. The reason is that a low height bridge lowers the strings of the bass violin and permits easy fingering without undue fatigue, whereas a high bridge raises the strings and renders playing more difficult and tiring.

Certain musical compositions require a plucking of the strings, and such plucking requires a high bridge; whereas lowering the bridge results in a softer tone from the bass violin. It is a known fact, however, that whether the bridge be high or low in a bass violin the pitch is not noticeably affected.

An object of the invention is to provide a bridge which is adjustable as to height and which permits easy playing of the bass violin under varying conditions.

Another object of the invention is to provide a bridge which is easily adjusted as to height above the deck of the bass violin whereby the string action may be adjusted to the player's desired.

A further object is to provide a bridge which is sturdy and rigid and at the same time adjustable as to height.

Another object is the provision of a bridge for use on a bass violin which does not mute the tone of the instrument.

A further object is the provision of a bridge so constructed and arranged as to be adjustable in height and in which novel indexing means is provided whereby the instrumentalist may, by use of said indexing means, readily adjust the bridge as to height to secure a given tension on the strings. With reference to this last object, it may be mentioned that every violin responds best to a certain height of bridge, and the present invention with its novel indexing means allows a desired height adjustment of the bridge.

Further objects include a bridge which is inexpensive in cost to manufacture, and which is generally superior to bridges now known to the inventor.

With the above mentioned and other objects in view the invention consists in the novel and useful provision, formation, construction, association and relative arrangement of parts, members and features, all as shown in a certain embodiment in the accompanying drawing, described

generally, and more particularly pointed out in the claims.

In the drawings:

Figure 1 is an elevation, partly in section, of the improved bridge;

Figure 2 is a sectional view on the line 2—2 of Figure 1; and

Figure 3 is a fragmentary front elevation of a bass violin incorporating the invention.

Referring now with particularity to the drawings, I have shown in Figure 3 a bass violin 1 incorporating the improved bridge 2, and over which the strings 3 are passed, the said strings being attached to pegs on the neck 4 of the violin and to a tail piece 5 on the body of the instrument.

The bridge 2 enables the instrumentalist to raise or lower the strings as desired without appreciably changing the pitch, and in such a manner as to maintain perfect string action at all times regardless of humidity or temperature of surrounding atmosphere.

The bridge 2 is usually formed of wood and is provided with a curved edge 6 having spaced transverse grooves 7 within which are received strings 3. As a rule such a bridge rests upon deck 8 of the violin. In the present instance I separate the bridge from the deck and provide feet 9 and 10 which engage the deck with elevating means designated generally as 11 interposed between the base 12 of the bridge and said feet. The bridge in the present instance does not deviate in form materially from that of the standard bridge now used on bass violins, in that it is provided with a transversely cutaway portion 13 of ornamental appearance, while the sides of the bridge are given a scroll-like surface at 14 and 15, terminating in the portions 16 and 17 which are usually integrally formed with the feet 9 and 10.

While not shown in the drawing, an end elevation of the bridge reveals that the side walls thereof taper from the base portion upwardly toward the grooves. This construction, however, is standard practice.

The deck 8 of the bass violin has a convex surface, as shown in Figure 1, and the bottoms 18 and 19 of the feet 9 and 10 correspond in contour to the deck.

The elevating means 11 includes a shaft 20 formed with an annular shoulder or flange 21 at some point along the length of the shaft, and the shaft is threaded on one side of said flange, as shown at 22, while that portion of the shaft on the opposite side of the flange 21 is smooth-

surfaced as shown at 23. Radially extending at equidistant points from the flange 21 are pins 24. These pins act as handle means whereby the shaft may be rotated. Secured on the threads of shaft portion 22 is an internally threaded bushing 25, one end of which is annularly flanged at 26. In the embodiment of the invention shown I provide preferably 20 threads to the inch, as this gives me a one-half inch adjustment in either direction for the bridge, as hereinafter pointed out. I have also found that a quarter-inch diameter shaft is very stable in the practice of the invention. I do not desire to confine my invention to any particular number of threads, nor shaft size, but make mention of a possible size as being one that has been found satisfactory.

Each foot 9 and 10 is bored, as indicated generally at 27, to frictionally and tightly receive the bushing 25, the annular flange 26 resting on the top surface of each foot. The bore in the foot extends from the top of the foot to the bottom thereof, although the bore beneath the bushing is reduced in diameter. The base portion, and particularly the portions 16 and 17 of the bridge, are bored as indicated at 28 and 29 to receive the smooth portion 23 of a shaft. The portions 28 and 29 closely approximate the diameter of the smooth portion of a shaft 23 so that there is considerable frictional engagement between said shaft portion and the wall bounding a bore. It is intended that the friction that exists between the wall bounding a bore in the bridge and the smooth portion of a shaft should be such as to cause considerable resistance to turning of the shaft. As shown, the length of the shaft portion 23 is such as to substantially fill the respective bores 28 and 29. The base portions of the bridge rest upon the top surface of the annular flanges 21.

The operation, uses and advantages of the invention are as follows:

One end of one of the radial pins or arms 24 is painted with a distinguishing color, such as a red or yellow, at 30. This provides what may be termed an "index" mark and will readily tell the instrumentalist how many turns he has made of the shaft, by noticing the index mark with reference to some base line. For instance, the index mark for both elevating means may point toward the instrumentalist when the instrumentalist is looking downwardly toward the bridge. He would therefore know that if he makes one complete revolution of the shaft he will have raised or lowered the bridge, depending upon the direction of rotation, $\frac{1}{20}$ ", if the twenty-threads-per-inch shaft is utilized. Quite obviously, any other thread pitch might be utilized, and the adjustment per revolution of the shaft would be correspondingly changed. I prefer, however, to allow for a one-half-inch adjustment of the bridge either up or down relative to the feet 9 and 10. Such a length of adjustment performs every function that the instrumentalist might desire, due to humidity or temperature change, which affect the strings, for practice work without undue fatigue, or for actual playing before an audience. The instrumentalist, having adjusted the bridge to the proper height may tune the bass violin in the usual manner by turning the pegs on the neck 4. Thereafter, by using the index mark 30 on each radial arm, adjustment of the shaft is effected by turning the shaft in either direction to raise or lower the bridge relative to the feet. As previously stated, such raising or lowering does not noticeably affect the pitch.

I claim:

1. In a device of the character disclosed, a bridge, a pair of feet adapted to rest on the deck of a bass violin, and an elevating means between each foot and said bridge; said elevating means in each instance having a shaft, one portion of which is threaded and a second portion of which is unthreaded, said bridge formed with bores to tightly receive the unthreaded portion of a shaft, and a threaded bushing positioned in each foot for receiving the threaded portion of a shaft.
2. In bass violin construction, a bridge over which the strings are passed, a pair of spaced feet resting on the deck of the bass violin, a pair of elevating means between said feet and said bridge for elevating or lowering the bridge relative to the feet, said elevating means including in each instance a shaft formed intermediate its length with an annular flange, a shaft portion on one side of said flange being threaded and a shaft portion on the opposite side being smooth-surfaced, said bridge formed with bores for tightly engaging and receiving the smooth-surfaced ends of the shafts, threaded bushings secured to said feet, said threaded bushings receiving the threaded portions of the shafts and a radial pin extending from each shaft flange for turning said shafts.
3. In bass violin construction, a bridge over which the strings are passed, a pair of spaced feet resting on the deck of the bass violin, a pair of elevating means between said feet and said bridge for elevating or lowering the bridge relative to the feet, said elevating means including in each instance a shaft formed intermediate its length with an annular flange, the shaft portion on one side of said flange being threaded and the shaft portion on the opposite side being smooth-surfaced; said bridge formed with bores for tightly engaging and receiving the smooth-surfaced ends of the shafts, threaded bushings secured to said feet, said threaded bushings receiving the threaded portions of the shafts and a radial pin extending from each shaft flange for turning said shafts, said radial pin provided with indexing means to indicate the degree of turning of a shaft.
4. In bass violin construction, a bridge over which the strings are passed, said bridge having a base portion and formed with bores extending inwardly of the bridge from said base portion, a pair of feet provided with bores, the said feet resting on the deck portion of the bass violin, with the bores in axial alignment with the bores of the bridge, shafts for positioning between the bores of the feet and the bridge, each shaft formed with a smooth surface and with a threaded area, said smooth surface adapted to be received within a bore of the bridge, and the diameter of a bore in the bridge and the diameter of the smooth surface of the shaft being substantially the same; threaded bushings for reception in the bores of said feet and for securing the threaded portion of each shaft, and an annular flange of each shaft and positioned between the threaded and smooth surface thereof, the said flange engaging the bridge.
5. In bass violin construction a bridge over which the strings are passed, said bridge having a base portion and formed with bores extending inwardly of the bridge from said base portion, a pair of feet provided with bores, the said feet resting on the deck portion of the bass violin, with the bores in axial alignment with the bores of the bridge, shafts for positioning between the

bores of the feet and the bridge, each shaft formed with a smooth surface and with a threaded area, said smooth surface adapted to be received within a bore of the bridge, and the diameter of a bore in the bridge and the diameter of the smooth surface of the shaft being substantially the same; threaded bushings for reception in the bores of said feet and for securing the threaded portion of each shaft, an annular flange on each shaft and positioned between the threaded and smooth surface thereof, the said flange engaging the bridge, and radial arms ex-

5 tending from the flanges whereby the shaft may be rotated.
